CLAIM

The ornamental design for a combined hair piece and clip, as shown and described.

DESCRIPTION

FIG. 1 is a perspective view of a combined hair piece and clip showing my new design;
FIG. 2 is a right side elevational view of thereof;
FIG. 3 is a rear elevational view thereof;
FIG. 4 is a top plan view thereof;
FIG. 5 is a front elevational view thereof;
FIG. 6 is a left side elevational view thereof; and,
FIG. 7 is an enlarged fragmentary perspective view of the opposite side of FIG. 4; the undisclosed portions of the hair tresses following the contours of the portions shown in the other views.

FIG. 1.

FIG. 2.

FIG. 3.

FIG. 4.

FIG. 5.

FIG. 7.

FIG. 6.
